[57] CLAIM

The ornamental design for a battery powered emergency warning light, as shown and described.

DESCRIPTION

FIG. 1 is a perspective view of a battery powered emergency warning light showing my new design;

FIG. 2 is a front elevational view thereof;

FIG. 3 is a rear elevational view thereof;

FIG. 4 is a side elevational view thereof, with the opposite side being a mirror image;

FIG. 5 is a top plan view thereof; and,

FIG. 6 is a bottom plan view thereof.

FIG.1.

FIG. 4

FIG. 6.

FIG. 5.
